Primary Examiner — Susan E Krakower*Assistant Examiner* — Jerry Shiuan-Hua Hsu(74) *Attorney, Agent, or Firm* — Harness, Dickey & Pierce, P.L.C.(57) **CLAIM**

The ornamental design for a set of trim panels, as shown and described.

DESCRIPTION

FIG. 1 is a right, front perspective view of a set of trim panels showing my new design;

FIG. 2 is a left, front perspective view thereof;

FIG. 3 is a left, rear perspective view thereof;

FIG. 4 is a right, rear perspective view thereof;

FIG. 5 is a left side view thereof;

FIG. 6 is a right side view thereof;

FIG. 7 is a top view thereof;

FIG. 8 is a bottom view thereof;

FIG. 9 is front view thereof; and,

FIG. 10 is a rear view thereof.

The broken lines illustrate environmental structure that forms no part of the claimed design.
